UNITED STATES PATENT OFFICE.

HARRY WEARNE, OF RIXHEIM, GERMANY.

DESIGN FOR WALL-PAPER.

SPECIFICATION forming part of Design No. 32,024, dated December 19, 1899.

Application filed November 24, 1899. Serial No. 738,232. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a plan view of a strip of wall-paper embodying the features of my design.

The leading feature of the design consists in a shell-panel decorated with mating doves and a basket containing flowers apparently suspended from the shell-panel.

The details of the design are as follows: The shell-panel has an embossed border and is decorated with two doves represented in the act of saluting and as resting upon a bow, the bow being supported on a quiver. Foliate

scrolls appear at each side of the shell-panel and apparently connected therewith, and at each of the scrolls bunches of flowers are arranged in such manner that the flowers appear adjacent to the shell-panel, as well as in close proximity to the scrolls. A fancy basket containing flowers of various types and provided with a handle is seemingly suspended from the shell-panel by a ribbon which is passed through the handle of the basket. 30

Having thus described my invention, I claim as new and desire to secure by Letters Patent—

The design for wall-paper as herein shown and described.

HARRY WEARNE.
